FOREIGN PATENT DOCUMENTS

CN 3616961 * 3/2007

Primary Examiner — John R Yeh*(74) Attorney, Agent, or Firm* — Wooshik Shim; Bold IP, PLLC(57) **CLAIM**

The ornamental design for a combined grill oiler and seamer, as shown and described.

DESCRIPTION

FIG. 1 is a front-top perspective view of a combined grill oiler and seamer;

FIG. 2 is a front-bottom perspective view thereof;

FIG. 3 is a front view thereof, the rear view thereof being a mirror image of the front view;

FIG. 4 is a top view thereof;

FIG. 5 is a left view thereof;

FIG. 6 is a right view thereof; and,

FIG. 7 is a bottom view thereof.

The broken lines in the figures illustrate portions of the combined grill oiler and seamer which form no part of the claimed design.

1 Claim, 7 Drawing Sheets(56)
